UNITED STATES PATENT OFFICE

HANS BERG, OF GRAND RAPIDS, MICHIGAN

DESIGN FOR A RADIOCABINET

Application filed January 15, 1930. Serial No. 34,137. Term of patent 3½ years.

To all whom it may concern:

Be it known that I, HANS BERG, a citizen of the United States, residing at No. 886 Floral Drive S. E., Grand Rapids, in the county of Kent and State of Michigan, have invented a new, original, and ornamental Design for a Radiocabinet, of which the following is a specification, reference being had to the accompanying drawing, forming a part hereof, in which—

Figure 1 is a front elevation of the radio cabinet, showing my new design;

Figure 2 is an end elevation of the same; and

Figure 3 is a diagrammatic front sectional view taken on line 3—3 of Figure 1.

I claim:

The ornamental design for a radio cabinet, substantially as shown.

HANS BERG.
